Primary Examiner — Ryan Harvey(74) *Attorney, Agent, or Firm* — McHale & Slavin, P.A.(57) **CLAIM**

The ornamental design for a pivoting exercise device, as shown and described.

DESCRIPTION

FIG. 1 is a perspective view of the pivoting exercise device of the instant invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of portions of the pivoting exercise device depicts environment and forms no part of the claim.

1 Claim, 5 Drawing Sheets(56)
